United States Patent Office

Des. 213,549
Patented Mar. 18, 1969

213,549

EXPLOSION SHIELD

Thomas P. Abbott, 18434 Topham St.,
Tarzana, Calif. 91356

Filed June 15, 1967, Ser. No. 7,481

Term of patent 14 years

U.S. Cl. D14—6
Int. Cl. D12—14; D29—99

FIGURE 1 is a top perspective view of the explosion shield, showing my new design;

FIGURE 2 is a bottom perspective view thereof;

FIGURE 3 is a top plan view thereof; and

FIGURE 4 is a side elevational view thereof.

I claim:

The ornamental design for an explosion shield, substantially as shown.
